TAPE RECORDER OR SIMILAR ARTICLE

Rod G. Bergstedt and Jan M. Farlow, Fort Wayne, Ind., assignors to The Magnavox Co., Fort Wayne, Ind., a corporation of Indiana

Filed Oct. 12, 1965, Ser. No. 87,443

Term of patent 7 years

(Cl. D26—14)

FIG. 1 is a left side, top and front isometric view of a tape recorder or similar article, showing our new design with the cover opened; and

FIG. 2 is a left side, top and front perspective view thereof with the cover closed.

The opposite side, not shown, is substantially a mirror image of the side shown and the back, not shown, is plain and unornamented.

We claim:

The ornamental design for a tape recorder or similar article, as shown and described.
